UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

WIRE-STAPLING MACHINE.

1,111,112.

Specification of Letters Patent. Patented Sept. 22, 1914.

Application filed June 9, 1905. Serial No. 264,377.

To all whom it may concern:

Be it known that I, HENRY WEBER, a citizen of the United States, residing at Chicago, county of Cook, and State of Illinois, have 5 invented certain new and useful Improvements in Wire-Stapling Machines, of which the following is a full, clear, and exact specification.

This invention relates to wire stapling machines of the class shown and described 10 in my U. S. Letters Patent No. 683,823, issued October 1, 1901, and is designed as an improvement thereon.

The improvements relate to the means for 15 guiding the wire properly into position on the anvil, as well as to features of minor importance hereinafter pointed out.

The anvil, in the usual machine of this class, is provided with a slot open at one side, 20 into which the wire is projected and rests, while a former which embraces the anvil, and, by engaging the projecting ends of the wire, turns said ends downwardly to produce the staple, which is thereafter forced 25 home by a suitable driver. This former has grooves in its opposed faces arranged lengthwise of its line of movement and in line with the inner end of the slot in the anvil, for receiving the ends of the staple and holding 30 and guiding the same while the staple is driven, and it is found to be quite difficult to induce the wire to at all times occupy a position directly in line with these grooves, however straight it might be at the start.

One object of the invention, therefore, is 35 to provide improved means for holding the wire in line with the wire grooves of the former after it is placed on the anvil or within the groove of the anvil.

With a view to the attainment of this end, 40 and the accomplishment of certain other objects which will hereinafter appear, the invention consists in certain features of novelty in the construction, combination, 45 and arrangement of parts, which will now be described with reference to the accompanying drawings, and more particularly pointed out in the claims.

In the said drawings, Figure 1 is a front 50 elevation of a part of a wire stapling machine, partially broken away, constructed according to this invention; Fig. 2 is a detail perspective view of a wire guide hereinafter described; Fig. 3 is an enlarged side

elevation of a part of a wire stapling ma- 55 chine embodying my invention, partially broken away, and disclosing the wire guide; Fig. 4 is a section taken on line 4, 4, of Fig. 1. Fig. 5 is a detail of the construction shown in the lower part of Fig. 4, to show the staple 60 former provided with grooves, with which the wire must come into alinement when it is properly positioned in the anvil member.

The wire from which the staples are formed may be stored on spool or reel, as 65 usual in machines of this type, and not necessary to illustrate or describe herein, and from this reel it is fed through suitable guide passages to a tube or passage, which is usually constituted by a section of tube 1, 70 screwed into the frame portion 2, for holding the wire preparatory to being severed by the wire knife 3, all as usual in machines of this kind. The wire in its passage to the tube 1 runs over a fixed support 4, over 75 which is arranged a holding dog in the form of a serrated wheel 5, pivoted in an arm 6 in such a manner that it may swing downwardly against the support 4, should the wire attempt to make a retrograde or back- 80 ward movement, and may freely move upwardly away from the support in the direction of feeding movement of the wire, the reverse rotation of the wheel 5 being prevented by any suitable means, such as a 85 set-screw 7 screwed through the side of the arm 6. From the support 4, the wire passes over a second support 8, which is suitably mounted upon a pair of guide-rods 9, 10, as usual, and over which support is arranged 90 a second dog in the form of a serrated wheel 11 mounted in a pivoted arm 12, as usual, acting like the arm 6 to allow the dog 11 to move upwardly in the direction of movement of the wire, but to grip the wire against 95 the seat or support 8 for preventing a relative rearward movement between the wire and the feeding dog. The support 8 is in the form of a slide mounted upon the guide-rods 9, 10, and is suitably connected to an 100 operating lever 13, pivoted at 14 to plate or head 15, and having an arm 16 arranged to be acted upon by cam 17, whereby the proper feeding movement will be imparted to the slide or support 8, and the wire will be 105 drawn from the reel between the support 4 and holding dog 5, and thereby projected through the guide-tube 1.

43 is the anvil, which, as usual, is provided with an open-sided slot 44 in its end, and is mounted in any suitable socket 45, and provided with a spring or cushion 46, whereby it may be moved longitudinally, it being held against rotary movement.

49 is the former, which is provided with side flanges 50, as usual, embracing a driver 51, and the opposed faces of these flanges 50 10 are provided with grooves 52 extending lengthwise of the line of movement of the former, and arranged directly over and in line with the inner end of the slot 44, the edges of the driver 51 being provided with tongues 53 fitting in said grooves 52, and thereby serving to guide the driver and hold it accurately in position with relation to the former and the anvil.

As the wire protrudes from the wire tube 20 1, it extends through the slot 44, and should rest therein directly in line with the grooves 52, so that as the former descends, the wire being clipped off, the ends of the wire projecting from the sides of the anvil will bend 25 downwardly and fit in the grooves 52, and will be thereby formed and at the same time held in position, while the driver 51 descends upon the upper end of the staple thus produced. It is quite obvious, therefore, that should the wire through any cause fail to assume a position accurately in line with the grooves 52, its ends will fail 30 to enter said grooves as the former descends, and the staple will not only be spoiled but 35 the machine will be clogged and the parts rendered inoperative. In order, therefore, that the accurate placement of the wire in line with the grooves 52 may be fully assured before the former descends into engagement with it, a wire guide 54 is arranged 40 at one side of the anvil, and provided with a bevel or rounded face 55, against which the end of the wire impinges, should the wire be the least out of line with 45 the grooves 52, the inner edge of the bevel 55 being so positioned with relation to the slot 44 in the anvil as to force the wire fully against the inner end of said slot. This guide 54, as better shown in Fig. 3, is 50 mounted on a pivot 56, so that it may swing toward and from the line of movement of the wire, and it is pressed toward the wire by any suitable spring 57, the guide and its spring 57, in this exemplification of the invention, being housed in a recess 58 formed in any suitable member 59 detachably secured over the former 49 and driver 51, and also, if desired, constituting a cover or 55 guide for the outer side of these parts, as well as limiting the outward movement of the anvil 43. The upper side of the anvil 43 is beveled, as shown at 60, so that the driver will push the same out of the way as it descends, and for the same purpose, one 60 side of the wire guide 54 is formed with a

beveled or rounded shoulder 61, upon which one side or flange of the former 49 descends, and thereby pushes the wire guide back into its recess after the ends of the staple enter the grooves 52.

The former 49 and the driver 51 may be operated as usual, or by any other suitable means. In the form of the invention shown in the drawing, the former is provided with a stud, which engages in the groove 63 of 75 the cam 17, while the driver is connected to a crank-pin 65 on the cam by means of a link 66 and a pin 67.

What I claim and desire to secure by Letters Patent is:

1. In a wire stapling machine, the combination with an anvil provided with a wire seat, a former for forming the wire over said anvil, and a driver for driving the staple after it is formed, of a wire guide contiguous to the anvil, and arranged to be engaged by the wire for holding the wire in position in its seat on the anvil and means for shifting the guide.

2. In a wire stapling machine, the combination with an anvil having a wire seat, a former for forming the staple over the anvil, and a driver for driving the staple, of a beveled wire guide having its bevel arranged to be engaged by the wire as it moves into 95 its seat on the anvil, for forcing the wire to its proper position in said seat and means for moving the guide out of engagement with the wire.

3. In a wire stapling machine, the combination with an anvil having a wire seat, a former for forming the staple over the anvil, and a driver for driving the staple, of a wire guide arranged at the side of the anvil and at the end of said wire seat, so as to be 105 struck by the advance end of the wire as it emerges from the side of the anvil and means for moving said guide.

4. In a wire stapling machine, the combination with an anvil having a wire seat, a 110 former for forming the staple over the anvil, having grooves for the ends of the staple, a wire guide arranged contiguous to the anvil in position to be impinged by the wire for forcing the wire into line with 115 said grooves and means for moving the guide out of engagement with the wire.

5. In a wire stapling machine, the combination with an anvil having a wire seat, a staple former for forming the wire over the 12 anvil, and a driver for driving the staple, of a wire guide arranged contiguous to the anvil and having a beveled face arranged to be struck by the wire for guiding the wire into its proper position upon said seat, and 12 a beveled shoulder arranged to be struck by the staple former, whereby the wire guide will be forced out of the way to permit the staple former to operate.

6. In a machine of the kind specified, the 1:

combination with staple forming devices including a staple forming plunger, of a spring-actuated wire guide mounted on said machine, its free end adjacent the path of said wire as said wire is fed through said forming devices, the free end of said wire guide being beveled on the surface presented to said wire and arranged to guide the end of said wire in its proper course, said wire 10 guide being free to be pushed out of the

path of the staple forming-plunger as same descends to form the staple.

In witness whereof, I have hereunto set my hand this 5th day of June 1905, in the presence of the subscribing witnesses.

HENRY WEBER.
